R. W. ANDERSON

RAIL MOUNTING

Filed Dec. 15, 1922

Inventor
ROBERT W. ANDERSON

Attorney
Walter J. Murray

UNITED STATES PATENT OFFICE.

ROBERT W. ANDERSON, OF COVINGTON, KENTUCKY.

RAIL MOUNTING.

Application filed December 15, 1922. Serial No. 607,057.

To all whom it may concern:

Be it known that I, ROBERT W. ANDERSON, a citizen of the United States of America, and a resident of Covington, in the county of Kenton and State of Kentucky, have invented a new and useful Improvement in a Rail Mounting, of which the following is a specification.

An object of my invention is to provide a device for precluding spreading of rails.

Another object of my invention is to provide a simple and efficient device for the purpose stated.

Another object of my invention is to provide a device wherein the spikes employed, so inter-lock with one another and with the rail that the objects stated will be accomplished with surety.

These and other objects are attained by the means described herein and disclosed in the accompanying drawings, in which—

Fig. 1 is a fragmental plan view of a rail and mounting therefor embodying my invention.

Fig. 2 is a sectional view on line 2—2 of Fig. 1.

Figs. 3, 4, 5 and 6 are detailed views of spikes forming details of my invention.

Fig. 7 is a plate forming a detail of my invention.

The tie 8 is of the ordinary wooden variety commonly employed, and has mounted upon it a plate 9 supporting a rail 10. The plate supports the rail upon its intermediate section 11, and has formed in it adjacent its ends, slots 12 and 13. The slots 12 and 13 are so disposed in relation to one another that the inner edges 14 and 15 of the slots 12 and 13 respectively, will be disposed immediately adjacent the side edges 16 and 17 of the base 18 of the rail, when the rail is mounted upon the plate as shown in Fig. 2. Three spikes, 19, 20 and 21 are employed in securing the rail and plate upon the tie. The spike 19 has wedge shaped lugs 22 and 23 formed upon its inner and outer faces 24 and 25 respectively. The lug 23 extends downwardly and outwardly from the head 26, and is of a length substantially equal to the thickness of the outer edge of the flange 27 forming part of the base 18 of

the rail. The lug 22 is of a wedge shape, extending upwardly and outwardly, and having its upper triangular face 28 disposed from the under face 29 of the head, at a distance substantially equal to the thickness of the flange 27 of the rail. The rail flange 27 is adapted to lie intermediate the flange 28 and the lower face 29 of the head when the spike is properly seated. The sides 30 and 31 of the lug 22 converge on a line 32 extending upwardly and outwardly of the shank 33 of the spike. The spike 20 carries a lug 34 upon its inner face 35, the lug 34 being substantially similar in structure and position upon spike 20 as is lug 22 upon spike 19. The rear 36 of the head 37 of the spike 20 extends slightly beyond the rear surface 38 of the spike 20 thereby providing a ledge or seat 39 upon the lower rear edge 70 of the head 37. The spike 21 is of the ordinary variety having a head 40 of a thickness such that when the spike is driven adjacent spike 20 as shown in Fig. 2, the upper rear edge 41 of the spike 21 will engage the 75 seat 39 formed on the spike 20.

It should be observed that the slot 13 is longer than is the slot 12. The slot 13 is made to accommodate spikes 20 and 21 while opening 12 is made only sufficiently large 80 to accommodate spike 19.

The rail 10 is mounted in the following manner. The plate is interposed between the base of the rail and the tie so as to have the slots 12 and 13 disposed upon opposite sides of the base of the rail. The spike 19 is then driven through slot 12 into the tie 8. As the lug 22 on the spike 19 enters the opening 12, the plate is moved transversely to the rail 10 to such extent that when the spike is driven to its limit, the lug 23 will engage the upper face 42 of the plate 11. Due to the fact that the wedge 22 has moved the upper end of the spike 19 away from the rail, to a slight distance, a blow upon the 90 head of the spike 19 will cause the wedge 22 to enter the tie and cause the spike 19 to assume the position shown in Fig. 2, wherein the lug 22 will be disposed below the flange 27 of the rail, and the flange will be lodged 100 between the lug 22 and the head 26. The spike 20 is then driven into the tie by way

- of the slot 13 of the plate 11. As the spike 20 is driven, the flange 43 of the rail is caused to lodge between the lug 34 and the head 37 of the spike 20 by the same method 5 as employed in lodging the flange 27 between the lug 22 and head of the spike. The spike 21 is then driven into the tie through the outer portion of the slot 13. Due to the fact that the rear ends of the heads of the 10 spikes 20 and 21 extend beyond the rear faces of said spikes, the spike 21 must be driven until its head 40 passes the head 37 of spike 20 and lodges below the head of spike 20.
- 15 By reference to Fig. 2 it will be readily apparent that the spikes 20 and 21 interlock, and that the rail 10 precludes upward creeping of the spikes. The spike, in turn 20 precludes spreading or lateral movement of the rail. The spikes 20 and 21 together with the base of the rail, lock the spike 19 against withdrawal from the tie.

When employing a structure as disclosed herein, it is unnecessary to secure the rail by 25 the means described herein, except at intervals of about five or six ties.

What I claim is:

1. In a rail mounting of the class described the combination of a tie, a slotted 30 plate, a rail having flanges, and spikes for engaging the flanges on the rail, adapted to pass through the slots in the plate and to be driven into the tie, the spikes being provided with means for cooperatively interlocking upon one another, and upon the 35 plate and rail, whereby to preclude lateral displacement of the rail.

2. A rail mounting of the class described comprising a tie, a flanged rail, a plate interposed between the rail flanges and the tie, and having slots formed in it, a slot lying 40 on each side of the rail, a spike for insertion in one of the slots in the plate and provided with means for engagement upon the plate 45 and the rail for resisting movement of the spike longitudinally of itself, and a pair of spikes for insertion in the slot at the other side of the rail provided with means for inter-locking upon one another and upon the rail flange.

3. In a mounting of the class described the combination of a tie, a flanged rail, a plate interposed between the rail flange and the tie having slots formed in it, a slot being 55 disposed on each side of the rail flange, a spike provided with a head, and with lugs upon its opposite sides, one lug having an upper face spaced from the head at a distance substantially equal to the thickness of the rail flange, whereby there is provided intermediate the head and said lug a recess for the reception of the rail flange, the other lug being provided with a face for engagement 60 upon the plate, said face extending in substantial alignment with the mentioned face

of the opposite lug, a second spike for insertion through the second slot in the plate adapted to be driven into the tie and having a head and a lug spaced from the head, the lug having a face adjacent the head and spaced therefrom at a distance substantially equal to the thickness of the rail flange the head projecting outwardly to form a seat on the side of the spike opposite to the lug, and a third spike for insertion through the last 70 mentioned slot and adapted to be driven into the tie, the third spike being provided with a head for engagement upon the plate and adapted to lodge in the seat formed on the second spike. 80

4. As a new article of manufacture a spike comprising a shank, a head at one end of the shank projecting outwardly from the shank, a lug extending outwardly from the shank and projecting in substantially the same direction as the head, the lug diverging toward the head and being of a substantially pyramidal form, having a face disposed adjacent the head, and having two side faces converging on a line drawn from 90 the apex of the lug to the shank. 85

5. As a new article of manufacture a spike comprising a shank, a head at one end of the shank projecting outwardly from the shank, a lug extending outwardly from the shank and projecting in substantially the same direction as the head, the lug diverging toward the head and being of a substantially pyramidal form, having a face disposed adjacent the head, and having two side faces converging on a line drawn from 95 the apex of the lug to the shank, the head also projecting from the side of the shank opposite to the side carrying the lug, whereby to provide a seat at the junction of the head and the shank. 100

6. As a new article of manufacture a spike comprising a shank, a head at one end of the shank projecting outwardly from the shank, a lug extending outwardly from the shank and projecting in substantially the same direction as the head, the lug diverging toward the head and being of a substantially pyramidal form, having a face disposed adjacent the head, and having two side faces converging on a line drawn from the apex of the lug to the shank, the shank carrying a second lug intermediate the first mentioned lug and the head, and disposed on the side of the spike opposite to the side thereof carrying the first mentioned lug. 110

7. As a new article of manufacture a spike comprising a shank, a head at one end of the shank projecting outwardly from the shank, a lug extending outwardly from the shank and projecting in substantially the same direction as the head, the lug diverging toward the head and being of a substantially pyramidal form, having a face disposed adjacent the head, and having two 120 side faces converging on a line drawn from the apex of the lug to the shank, the shank carrying a second lug intermediate the first mentioned lug and the head, and disposed on the side of the spike opposite to the side thereof carrying the first mentioned lug. 125

130

side faces converging on a line drawn from the apex of the lug to the shank, the shank carrying a second lug intermediate the first mentioned lug of the head and disposed on 5 the side of the spike opposite to the side thereof carrying the first mentioned lug, the second mentioned lug having its face far-

thest removed from the head, extending in substantial alignment with the first mentioned face of the first mentioned lug. 10

In testimony whereof, I have hereunto subscribed my name this 8th day of December, 1922.

ROBERT W. ANDERSON.
